UNITED STATES PATENT OFFICE

2,132,302

LAMP STRUCTURE

Jeremiah D. Kennelly, Oak Park, Ill.

Application April 3, 1936, Serial No. 72,652

1 Claim. (Cl. 240—48)

This invention relates particularly to lamp structures adapted for use on motor vehicles or the like. The invention is well adapted, for example, for use on police motor vehicles, fire trucks, or in other situations where warning signals are desirable.

In some respects, the invention constitutes an improvement upon the invention disclosed and claimed in my U. S. Patent 1,991,101, granted

February 12, 1935.

The primary object is to provide a simple lamp structure of the character suggested which will operate in a highly effective manner to cast a warning beam in front, for example, of a fire truck, or other motor-driven vehicle.

An important feature of the invention is the provision of a simple and desirable device for maintaining a circuit to the electric bulb of a lamp which is being oscillated about a vertical axis; a further feature of improvement is the provision of a mounting for the lamp bulb which is adapted to oscillate about a horizontal axis, the reflector in which the bulb is located being, in this instance, stationary; and a further feature of the invention is an improved device which provides for variation of the course of the beam of light without the necessity of physically tilting the bulb or the reflector in which the bulb is mounted to raise and lower the beam of light.

A more complete description of the features of improvement will appear in the description which follows.

The invention is illustrated in the accompanying drawings, in which—

Fig. 1 is a broken vertical sectional view illustrating a lamp device constructed in accordance with my invention; Fig. 2, a broken horizontal sectional view taken as indicated at line 2 of Fig. 1, illustrating the manner in which a circuit is maintained during oscillation of the lamp-casing; Fig. 3, a broken horizontal section taken as indicated at line 3 of Fig. 1; Fig. 4, a broken horizontal section taken as indicated at line 4 of Fig. 1; and Fig. 5, a vertical sectional view, partly in elevation, illustrating a modification.

Referring to Figs. 1-4, A designates a frame, shown as in the form of a casing, which is adapted to be mounted, for example, upon suitable supporting forks at the front end of a motor vehicle; B, a lamp-casing equipped with a depending shaft B' journaled to oscillate in the front portion of the frame A; C, a lamp-bulb mounting carrying a lamp-bulb C' adapted to be oscillated in the rear portion of the reflector; D, a motor mounted in the rear portion of the

casing-like frame A; and D', motor-driven mechanism serving to oscillate the shaft B' and also to oscillate the lamp-mounting C.

One terminal of the lamp and one terminal of the motor are grounded, preferably.

The lamp casing B is provided at its lower portion with an opening, as indicated at 1, into which projects a flange with which the upper portion of a disk-like cap plate 2 is provided. The shaft B' extends through the cap-plate and is secured thereon by nuts 3. Preferably a ball-bearing 4 supports the shaft B' and the lamp carried thereby.

The lower end of the shaft B' is equipped with an arm 5 with which is pivotally connected a link 6 provided with a depending pivot-member 6a.

The mounting C of the lamp-bulb extends freely through an opening 7 in the rear portion of the reflector 7a which is fixedly mounted in the lamp-casing; and the mounting is connected by a transverse pivot 8 with the hollow neck portion 7b of the reflector. The mounting C is shown equipped with a clamping ring 9 which is connected by a link 10 with a vertical plunger 11 which works freely through the shaft B'.

The outer terminal of the lamp-bulb is grounded through the mounting C and its connections. The central terminal of the plug-portion 12 of the lamp bulb makes the usual contact with the adapter C and is electrically connected, in a known manner, with a conductor wire 13 which extends downwardly through the shaft B' to a contact-carrier 14 which is insulatingly supported by the lower end of the shaft B'. As illustrated in Fig. 2, the member 14 is attached to an enlargement at the lower end of the shaft B', as by means of screws 15, suitably insulated. An insulation disk 16 is interposed between the member 14 and the lower end of the shaft.

The member 14 carries a spring-projected contact-member 14a which is yieldingly held against a curved, segmental contact-member 17 which is insulatingly connected with the frame A at points 17a.

As will be understood from Figs. 1 and 2, the conductor 13 preferably extends through an opening in the disk 14 and has a bared end which is electrically connected with the disk 14 by means of one of the screws 15. Thus, current may be passed continuously upward to the lamp bulb, notwithstanding the oscillation of the lamp in a horizontal plane.

The lower end of the plunger 11 is engaged

by a bell crank lever 18 adapted to be actuated by a link 19.

The motor D has a shaft equipped with a worm 20 which serves to actuate a worm-wheel 21 5 journaled on a vertical axis and a worm-wheel 22 journaled on a horizontal axis. The pivot-member 6^a of the link 6 is eccentrically connected with the worm-wheel 21. That is, the member 6^a serves as a crank for actuating the arm 5 and 10 effecting oscillation of the shaft B'.

The link 19 is connected by an eccentric pin 19^a with the worm-wheel 22, and thus the bell-crank lever 18 will be oscillated by the rotation of the wheel 22.

15 Current is supplied to the motor and lamp through a conductor 23 which has a branch 23^a leading to the motor and a branch 23^b which is electrically connected with the segmental contact 17 through the medium of one of the bolts 24 20 which serve to connect the segment insulatingly to the frame A.

25 The base frame, which constitutes a housing for the motor and the driving mechanism actuated by the motor, is shown provided with perforate lugs 25 by means of which the frame may be securely mounted upon forks or brackets at the front end of the motor vehicle.

30 Current may be supplied from any suitable source. In connection with Fig. 1, 26 indicates a battery having one terminal grounded at 27. Current from the battery may be passed through a switch 28 to the conductor 23. From the description given, it will be understood that as the motor operates, the worm 20 actuates the worm-wheels 21 and 22 continuously, thus causing the 35 lamp casing to oscillate about a vertical axis and causing the lamp bulb to oscillate about a horizontal axis. The effect is to cause the beam of light thrown by the lamp to cross itself. Any 40 desired timing of the oscillations about the vertical axis with respect to the oscillations about a horizontal axis may be employed. It is possible, by selecting a suitable gear ratio, to produce a figure 8 configuration of the beam-path, 45 as more fully explained in the above-mentioned patent.

50 In the modification shown in Fig. 5, the general construction is the same as already described, and corresponding parts are designated by corresponding reference characters. In this case, the oscillating lamp-bulb mounting is dispensed with. Instead, an adapter C² is longitudinally adjustable, for focusing purposes, in a sleeve 29 with which the rear portion of the 55 fixedly mounted reflector is provided. The adapter, or mounting, carries a lamp-bulb C³ which is provided with filaments 30 and 31, spaced one above the other.

The construction shown in Fig. 5 provides for

5 alternate energizing of the filaments 30 and 31, thus alternately raising and lowering the light-emitting source. The outer terminal of the plug-portion of the lamp, designated 32, is grounded through the reflector and lamp casing. The 10 central or intermediate terminals of the filaments 30 and 31 are designated 30^a and 31^a respectively. They contact with members 33 and 34 which are electrically connected with conductors 33^a and 34^a which lead downwardly 15 through the shaft B' which carries the lamp-casing. The shaft B is oscillated through the medium of the worm-wheel 21 in the manner described in connection with Figs. 1-4. A worm-wheel 22^a replaces the worm-wheel 22 of the other construction and serves to actuate a cam-segment 35 which is adapted to alternately close switches 36 and 37 which are mounted in the casing-like frame A. The switch 36 controls the energizing of the conductor 33^a; and the switch 20 37 controls the energizing of the conductor 34^a. As stated, the filaments 30 and 31 are alternately energized and heated to incandescence. Owing to the fact that the filaments are located in different horizontal planes, or at different 25 levels, the effect is to cause an up-and-down movement of the beam as the filaments are alternately energized. Also, an interruption of the light occurs, the length of interruption depending upon the length of the arc of the segment 35 which closes the switches in alternation. Preferably, the interruption is long enough to enable the interruption to be readily detected by the eye, so that distinct flashes are 30 noticeable.

35 The foregoing detailed description has been given for clearness of understanding only, and no unnecessary limitations should be understood therefrom.

40 What I claim as new and desire to secure by Letters Patent is:

45 In a signal lamp device of the character set forth, a motor casing, a motor therein, a lamp casing supported by said motor casing, a reflector fixedly supported in said lamp casing, said reflector being centrally apertured at its rear side, a lamp bulb mounting extending through and 50 pivotally supported on a horizontal axis within said aperture for vertical oscillatory movement therein, said mounting having a rearwardly extending shank portion of substantially uniform diameter, a light bulb in said mounting, a clamping ring mounted on said shank and adjustable therealong toward and away from the pivot of said mounting whereby to vary the throw of said 55 light bulb, and actuating means, driven by said motor and connected to said clamping ring.

JEREMIAH D. KENNELLY.
